UNITED STATES PATENT OFFICE.

CHARLES HIBBARD AND WARREN HIBBARD, OF SANDYHILL, NEW YORK,
ASSIGNORS TO HIBBARD GAS ENGINE CO., OF SANDYHILL, NEW YORK.

VAPORIZER.

No. 811,397.

Specification of Letters Patent.

Patented Jan. 30, 1906.

Application filed November 15, 1904. Serial No. 232,827.

To all whom it may concern:

Be it known that we, CHARLES HIBBARD and WARREN HIBBARD, citizens of the United States, and residents of Sandyhill, in the county of Washington and State of New York, have invented a new and Improved Vaporizer, of which the following is a full, clear, and exact description.

The invention relates to explosion-engines; and its object is to provide a new and improved vaporizer or mixing-valve arranged to insure a quick and complete vaporization of the liquid fuel (gasolene) and an intimate mixture of the proper amount of air and vapor and to prevent flooding of the device by the liquid fuel and frosting of the liquid-fuel chamber in cold weather.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement on the line 1 1 of Fig. 3. Fig. 2 is a transverse section of the same on the line 2 2 of Fig. 3. Fig. 3 is a sectional plan view of the same on the line 3 3 of Fig. 1, and Fig. 4 is a like view of the same on the line 4 4 of Fig. 1.

In the casing A of the vaporizer are formed an air-chamber B and a mixing-chamber C, connected with each other by a valve-port controlled by an air-valve E, adapted to be seated on the valve-seat D, and centrally within the said air-chamber B is secured a vessel F for containing gasolene or other liquid fuel, the said vessel being connected at its bottom by an outlet G with the mixing-chamber C, the terminal of the said outlet forming a valve-seat G', normally closed by the liquid-fuel valve H. The air-valve E is in the form of a ring-shaped leather valve secured to a metal body E', having a stem E² mounted to slide vertically in a bearing formed on the bottom cap A' of the casing A, the said body E being pressed on by a spring H³, seated on the cap A' and serving to normally hold the valve E to its seat D. The liquid-fuel valve H is in the form of a cup-shaped metallic body H', having a stem H² mounted to

slide in the hollow stem E² and pressed on by a spring H³, seated on the upper end of a regulating-screw H⁴, screwing in the lower portion of the stem E² and extending to the outside of the vaporizer to allow the operator to regulate the tension of the spring H³. A ring-shaped cap-plate E⁴ is arranged on the top of the valve E and is secured to the body E' by screws, bolts, or other fastening means E⁵, and the inner edge of the said cap-plate E⁴ extends over the top edge of the cup-shaped body H', but is spaced therefrom when the valves E and H are seated on their seats D and G'. (See Figs. 1 and 2.) When the valve E is moved downward off its seat D, then the valve H remains on its seat G' until the cap-plate E⁴ engages the body H', and then on a further downward or opening movement of the valve E the valve H is carried along—that is, is moved off its seat G'—after the valve E has moved off its seat. When the valve E returns, the valve H seats itself sooner than the valve E to close the outlet G prior to the valve E moving to its valve-seat D—that is, disconnecting the chambers B and C from each other.

In the outlet G is arranged a manually-controlled needle-valve I for regulating the amount of liquid fuel passing from the vessel F to the mixing-chamber C. The liquid fuel is conducted from an overhead-supply by way of a supply-pipe J to an inlet K, opening into the bottom of the vessel F, the said inlet K being partly formed in the casing A and partly in the bottom of the vessel F, and the said inlet K is controlled by a valve L, having its valve-stem L' attached to a float L² and located within the vessel F and rising and falling therein with the liquid fuel in the said vessel, it being understood that when the liquid fuel falls below a predetermined level then the float sinks and the valve L is opened to admit liquid to the vessel F, and when the liquid rises in the vessel and reaches the predetermined level therein then the float in rising correspondingly causes the valve L to close the inlet K.

The air-chamber B is provided in its side wall with inlet-openings B' and B², of which the inlet-opening B' may be connected by a pipe N with any suitable warm-air supply, so as to permit warm air to pass into the said chamber B. The other opening B² leads to the atmosphere, and the said openings B' and

B² are controlled by a segmental valve O, having a knob O' extending through an elongated slot A², formed in the casing, to allow the operator to shift the valve O so as to open 5 either inlet B' or B² to the chamber B, thereby admitting either warm air or ordinary atmospheric air to the chamber B.

The side wall of the mixing-chamber C is provided with an outlet-opening C', connected 10 by a pipe P with the working chamber of the explosion-engine, so that when the device is in use on the explosion-engine and the piston thereof is on the suction-stroke then the valve E is caused to move downward against the tension of its spring E³, so as to connect 15 the air-chamber B with the mixing-chamber C, the said valve E after being opened a short distance carrying the liquid-fuel valve H along; so as to open the outlet G to permit 20 gasoline or like liquid fuel to flow from the vessel F onto the top of the open valve H for the air from the chamber B to vaporize the said gasoline and to carry the same along down into the chamber C, from which the 25 mixture can pass by the pipe P into the working chamber of the engine. At the end of the suction-stroke of the piston the valve E³ returns the valve E to its seat, and in doing so the valve H is moved by its spring H³ 30 onto its seat G' immediately previous to the valve E being finally seated on its valve-seat D.

By the arrangement described the flow of 35 the liquid fuel into the mixing-chamber C does not begin until after the valve E is opened, and the flow of the liquid is cut off previous to the valve E moving back to its seat, so that any possible flooding of the vaporizer by the liquid fuel is completely prevented.

By having the vessel F containing the liquid fuel surrounded by the chamber B it is evident that the said vessel F is externally warmed by the entering warm air to prevent 45 frosting of the said vessel and chilling of the gasoline contained therein, and consequently a proper and quick vaporization of the liquid fuel takes place whenever the valve H is opened, as previously explained.

50 In case any liquid fuel is not vaporized and passes into the mixing-chamber C it settles in an annular recess A³, formed on the upper face of the cap A', and from the bottom of this recess A³ leads a pipe Q, discharging into 55 the top of the vessel F, so that the said non-vaporized liquid fuel is forced back into the vessel F whenever the piston in the cylinder of the engine is on the return stroke. This arrangement for forcing the non-vaporized 60 liquid fuel back into the vessel F is valuable when used in connection with the two-cycle engine with one vaporizer for each cylinder of the engine, in which case there would be no check-valve between the vaporizer and 65 mixing-chamber or crank-case of the engine.

It is understood that the float L fits sufficiently loosely in the vessel F to allow the liquid forced back by way of the pipe Q to mix with the liquid contained in the said vessel. 70

Having thus described our invention, we claim as new and desire to secure by Letters Patent—

1. A vaporizer for explosion-engines comprising a vessel for containing the liquid fuel and having an outlet, an air-chamber surrounding the said vessel and having a valve-port and a valve-seat, a mixing-chamber connected with the working chamber of the engine and into which open the said port of the air-chamber and the said outlet of the vessel, an air-valve controlling the said valve-port and adapted to be opened by the suction action of the engine, and a liquid-fuel valve for the said outlet of the vessel, opened by the said air-valve after the latter has moved off its seat, and closing previous to the air-valve moving to its seat. 80

2. A vaporizer for explosion-engines comprising a vessel for containing the liquid fuel and having an outlet, an air-chamber surrounding said vessel and having a valve-port and a valve-seat, a mixing-chamber connected with the working chamber of the engine and into which open the said port and the said outlet, an air-valve controlling the said valve-port and adapted to be opened by the suction action of the engine, a liquid-fuel valve for the said outlet, opened by the said air-valve after the latter has moved off its seat, and closing previous to the air-valve moving to its seat, a spring for holding the said air-valve to its seat, and a spring for holding the said liquid-fuel valve to its seat. 90

3. A vaporizer for explosion-engines comprising a vessel for containing the liquid fuel and having an outlet, an air-chamber surrounding the said vessel and having a valve-port and a valve-seat, a mixing-chamber connected with the working chamber of the engine and into which open the said port and the said outlet, an air-valve controlling the said valve-port and adapted to be opened by the suction action of the engine, a liquid-fuel valve for the said outlet, opened by the said air-valve after the latter has moved off its seat, and closing previous to the air-valve moving to its seat, a spring for holding the said air-valve to its seat, a spring for holding the said liquid-fuel valve to its seat, and means for adjusting the tension of the spring for the said liquid-fuel valve. 105

4. A vaporizer for explosion-engines comprising a vessel for containing the liquid fuel and having an outlet, an air-chamber having a valve-port and a valve-seat, a mixing-chamber connected with the working chamber of the engine and into which open the said port and the said outlet, an air-valve controlling the said valve-port and adapted to be opened 115

by the suction action of the engine, a liquid-fuel valve for the said outlet, opened by the said air-valve after the latter has moved off its seat, and closing previous to the air-valve 5 moving to its seat, and a connection leading from the said mixing-chamber to the said vessel, to force any non-vaporized liquid fuel that passes into the mixing-chamber back into the said vessel by pressure from the engine on the 10 return stroke of the engine-piston.

5. A vaporizer for explosion-engines comprising a vessel for containing the liquid fuel and having an outlet, an air-chamber surrounding said vessel and having a valve-port 15 and a valve-seat, a mixing-chamber connected with the working chamber of the engine and into which open the said port and the said outlet, an air-valve controlling the said valve-port and adapted to be opened by the 20 suction action of the engine, a liquid-fuel valve for the said outlet, opened by the said air-valve after the latter has moved off its seat, and closing previous to the air-valve moving to its seat, a liquid-fuel supply for 25 the said vessel, a supply-valve in the said supply, and a float in the said vessel, connected with the said supply-valve to maintain a uniform level of the liquid fuel in the said vessel.

30 6. A vaporizer for explosion-engines provided with a vessel for containing liquid fuel, an air-chamber surrounding the said vessel, a mixing-chamber into which open the said vessel and the said air-chamber, and valves 35 controlling the connections between the said mixing-chamber and the said air-chamber and vessel.

7. A vaporizer for explosion-engines provided with a vessel for containing liquid fuel and having an outlet at its bottom, an air-chamber having a valve-seat around the 40 said outlet, an air-valve having a ring-shaped leather valve adapted to be seated on the said seat, and a liquid-fuel valve having a disk leather valve adapted to be seated on the said outlet, the said disk leather valve being arranged within the opening of the said ring-shaped leather valve.

8. A vaporizer for explosion-engines provided with a vessel for containing liquid fuel and having an outlet at its bottom, an air-chamber having a valve-seat around the said outlet, an air-valve having a ring-shaped leather valve adapted to be seated on the 50 said seat, and a liquid-fuel valve having a disk leather valve adapted to be seated on the said outlet, the said disk leather valve being arranged within the opening of the said ring-shaped leather valve, the said air-valve and 55 the said liquid-fuel valve having spring-pressed metallic bodies for supporting the said leather valves.

60 9. A vaporizer for explosion-engines pro-

vided with a vessel for containing liquid fuel and having an outlet at its bottom, an air-chamber having a valve-seat around the said outlet, an air-valve having a ring-shaped leather valve adapted to be seated on the said seat, and a liquid-fuel valve having a disk leather valve adapted to be seated on the 65 said outlet, the said disk leather valve being arranged within the opening of the said ring-shaped leather valve, the said air-valve and the said liquid-fuel valve having spring-pressed metallic bodies for supporting the 70 said leather valves, the body of the said liquid-fuel valve being held to slide in the body of the said air-valve.

10. A vaporizer for explosion-engines provided with a vessel for containing liquid fuel 80 and having an outlet at its bottom, an air-chamber having a valve-seat around the said outlet, an air-valve having a ring-shaped leather valve adapted to be seated on the said seat, and a liquid-fuel valve having a disk 85 leather valve adapted to be seated on the said outlet, the said disk leather valve being arranged within the opening of the said ring-shaped leather valve, the said air-valve and the said liquid-fuel valve having spring-pressed metallic bodies for supporting the 90 said leather valves, the body of the said liquid-fuel valve being held to slide in the body of the said air-valve, and the latter having means for carrying the liquid-fuel valve 95 along when moving into an opening position.

11. A vaporizer for explosion-engines provided with a vessel for containing liquid fuel and having an outlet at its bottom, an air-chamber having a valve-seat around the said 100 outlet, an air-valve having a ring-shaped leather valve adapted to be seated on the said seat, and a liquid-fuel valve having a disk leather valve adapted to be seated on the said outlet, the said disk leather valve 105 being arranged within the opening of the said ring-shaped leather valve, the said air-valve and the said liquid-fuel valve having spring-pressed metallic bodies for supporting the 110 said leather valves, the body of the said liquid-fuel valve being held to slide in the body of the said air-valve, and the latter having means for carrying the liquid-fuel valve along when moving into an opening position, the 115 said means being arranged to open the liquid-fuel valve after the air-valve has moved off its seat and to allow the liquid-fuel valve to close ahead of the air-valve.

In testimony whereof we have signed our names to this specification in the presence of 120 two subscribing witnesses.
